UNITED STATES PATENT OFFICE.

LINDLEY S. LAWSON, OF HOMESTEAD, PENNSYLVANIA, ASSIGNOR TO LAWSON MANUFACTURING COMPANY, OF HOMESTEAD, PENNSYLVANIA, A CORPORATION OF PENNSYLVANIA.

WATER-HEATER.

1,172,028.

Specification of Letters Patent. Patented Feb. 15, 1916.

Application filed November 18, 1914. Serial No. 872,741.

To all whom it may concern:

Be it known that I, LINDLEY S. LAWSON, a citizen of the United States, and resident of Homestead, in the county of Allegheny and State of Pennsylvania, have invented certain new and useful Improvements in Water-Heaters, of which the following is a specification.

This invention relates to a water heater for use in connection with stand boilers and other containers, the apparatus including a gas-heated coil through which the boiler-contained water circulates, and one object is to provide improved apparatus of compact form, the casing of which incloses a gas burner having an inlet at one side of the casing whereby the burner and its connections are more conveniently accessible than in those forms of heaters wherein the burner inlet extends downwardly beneath the casing.

A further purpose is to provide improved means for removably supporting the circulation coil and the burner within the casing; also to so construct the casing that the coupling-carrying lower extremity of the coil may be readily inserted, with means for closing the opening through which the coupling passes.

In the accompanying drawings, Figure 1 is a view of a heater embodying the invention, the same being shown partly in elevation with the door-forming portion of the casing open, and partly in vertical section. Fig. 2 is a sectional plan taken on line 2—2 of Fig. 1, the burner inlet being shown in section. Fig. 3 is a sectional elevation of one side of the upper portion of the heater taken at right angles to Fig. 1, and Fig. 4 is a similar view of the lower portion of the heater taken on line 4—4 of Fig. 1.

Referring to the drawings, the upright inclosing casing is divided vertically, 2 designating the portion thereof which constitutes a support for the heater mechanism, and 3 is the hinged door-forming portion. Casing part 2 supports a crown 4 of conventional form having the usual flue connection 5, and at one side of the latter is an opening 6 for the upper extremity of the circulation coil 7. With the casing open as in Fig. 1, the coil is adapted to be entered in the support-forming part 2, the coil being sustained therein by its lower convolutions resting on lugs 8 at the inner side of the casing. The coil is confined on the supporting lugs

by a clip 10 which is removably secured to the inner side of the casing between lugs 11 by bolt 12. Said clip engages one of the lower convolutions of the coil, and a similar clip 10' engages one of the upper convolutions, so that the coil of relatively thin copper tubing is firmly held in place.

The coil is preferably of spool form, being of smallest diameter midway its ends, and in the plane of this smallest-diameter portion part 2 of the casing is formed with the encircling inwardly-projecting rib or vane 2', and door part 3 with a corresponding rib 3'. When the casing is closed ribs 2' and 3' comprise a baffle for the ascending heat currents, directing them inwardly toward the coil and thereby increasing the efficiency of the heater.

The lower extremity 7' of the coil is fitted with a coupling element 13 which is ordinarily applied thereto before the heater is assembled, and in order that the coil may be inserted in the casing the support-forming portion 2 thereof is formed with an opening 14 of sufficient size to pass the coupling, the opening being closed by the gate or plate 15 which fits around coil extremity 7', Figs. 1 and 4.

The hollow burner 16 is of general star-form with air passages 17 between its arm-like branches, also a central air passage 18. The mixer tube 19 projects laterally from the burner body through a socket-like opening 20 near the bottom of one edge of casing part 2. The connections for the burner are thus located at one side of the heater and are more conveniently accessible than with the burner connections extending upwardly from beneath the heater as has heretofore been customary. Also, with the improved construction the heater may stand on the floor or be arranged closer thereto than is possible with the old form of burner connections. The mixer tube also cooperates with burner lugs 21 and 22 in supporting the burner within the casing, lug 21 being adapted to enter a notch or recess 21' in the vertical edge of casing part 2 opposite the mixer tube, and lug 22 being adapted to pass through an opening 22' in said casing part beneath the coil extremity 7', Figs. 2 and 4. Lug 22 is apertured to receive a cotter 23 which holds the burner in place when the casing is opened as in Fig. 1. Mixer tube 19 and lug 21 being at

the juncture of the casing sections, when door section 3 is opened it is only necessary to displace cotter 23 and the burner may be removed in its entirety. And with the door open the circulation coil may be readily taken out by removing gate 15 and releasing clip 10, crown 4 being released by removing its securing bolts 4' to permit withdrawal of the upper extremity of the coil extremity carrying coupling element 18'.

A pan 24 is suspended beneath the burner for catching condensate which drips from the coil, the condensate evaporating before the pan can overflow. The pan may be conveniently supported by bolt 25 which secures it to lug 26 projecting in the burner air passage 18. Openings 24' in the pan admit air in sufficient amount for the burner. The drip pan thus mounted is in effect a portion of the burner, being inserted and removed therewith.

The several novel features herein described combine to produce a heater of simple and compact construction in which the several parts are readily accessible and with the parts conveniently arranged for assembling and for taking apart.

I claim:

1. In a water heater, the combination of an upright casing adapted to open at one side, coil-supporting devices at the inner side of the casing, an upright circulation coil adapted to be moved sidewise into the casing through its open side with convolutions of the coil removably engaging said supporting devices, and clips removably secured to the interior of the casing and engaging the coil and removably holding the same in position on the coil-supporting devices.

2. In a water heater, the combination of an upright open-bottom casing, an upright circulation coil spaced upwardly from the lower end of the casing, a gas burner beneath the coil, the burner having a laterally disposed fuel inlet and the casing formed

above its lower extremity with a side opening through which said fuel inlet extends, and a drip pan beneath the burner and fitting and closing the lower end of the casing, the pan formed with vertical air passages of such area as to supply the requisite amount of air to the burner.

3. In a water heater, the combination of a vertically divided upright casing with one portion thereof comprising a coil support and the other portion comprising a door, coil-sustaining lugs spaced apart and projecting from the inner wall of the coil-supporting casing section, an upright circulation coil adapted to be entered through the open side of said casing section and rest on the supporting lugs thereof, and clips removably secured to the inner side of said casing section and embrace the upper and lower portions of the coil and hold the latter in position on said lugs, and a burner supported beneath the casing.

4. In a water heater, the combination of a vertically divided casing with one section thereof comprising a support and with the other section comprising a door, the support-forming portion of the casing formed with a passage which intersects the joint between the two portions of the casing, a circulation coil adapted to be sustained within the support-forming portion of the casing, and a burner adapted to be entered in the support-forming portion of the casing when the door portion thereof is open, the burner having a laterally extending mixer tube which is adapted to be entered in said joint-intersecting opening in the casing and be confined therein when the door-forming portion of the casing is closed.

In testimony whereof, I affix my signature in presence of two witnesses.

LINDLEY S. LAWSON.
